DESIGN FOR A SHIRT OR SIMILAR ARTICLE

Laura B. Patterson, New York, N. Y.

Application January 21, 1941, Serial No. 98,196

Term of patent 3½ years

To all whom it may concern:

Be it known that I, Laura B. Patterson, a citizen of the United States of America, residing in New York city, county of New York, and State of New York, have invented a new, original, and ornamental Design for a Shirt or Similar Article, of which the following is a specification, reference being had to the accompanying drawing, forming part thereof, wherein: article showing my new design with an open collar.

Figure 2 is a front view thereof showing the collar closed.

The back of the shirt is conventionally plain.

I claim:

The ornamental design for a shirt or similar article, substantially as shown and described.

LAURA B. PATTERSON.
